(57) CLAIM

The ornamental design for a device for reshaping skin, as shown and described.

DESCRIPTION

FIG. 1 is a left front perspective view of a device for reshaping skin, showing our new design;

FIG. 2 is a bottom view thereof;

FIG. 3 is a right front perspective view thereof;

FIG. 4 is a right side view thereof;

FIG. 5 is a front view thereof;

FIG. 6 is a left side view thereof;

FIG. 7 is a bottom left perspective view thereof;

FIG. 8 is a top view thereof; and,

FIG. 9 is a bottom right perspective view thereof.

The broken lines illustrate portions of the device for reshaping skin and form no part of the claimed design.
